UNITED STATES PATENT OFFICE.

WALTER J. F. LIDDELL, OF CHARLOTTE, NORTH CAROLINA.

SAW-GUIDE.

SPECIFICATION forming part of Letters Patent No. 292,381, dated January 22, 1884.

Application filed December 1, 1883. (No model.)

To all whom it may concern:

Be it known that I, WALTER J. F. LIDDELL, of Charlotte, county of Mecklenburg, State of North Carolina, have invented a new and useful Improvement in Saw-Guides, of which the following is a full, clear, and exact description, reference being had to the accompanying drawings, making part of this specification.

10 My invention relates to a new and useful improvement in guides for circular saws, adapted to be adjusted easily and quickly to accommodate itself to the cut of the saw, for the purpose of guiding and steadyng the latter; also, to means whereby said guide may be moved out of proximity with the cut of the saw, and whereby one arm of said guide may be moved away from the saw independently of the other arm when it is desired to remove 15 the saw itself for sharpening or other purposes; and it consists in certain features and details of construction and arrangement, hereinafter fully set forth, whereby said guide is rendered capable of being adjusted with ease and rapidity, at the same time providing a saw-guide which is inexpensive and durable, and which is also simple in construction.

In the accompanying drawings, Figure 1 represents a side elevation of the saw-frame and 30 saw with my improvements applied thereto. Fig. 2 is a plan view of a portion of the same; Fig. 3, a transverse section, and Figs. 4 and 5 enlarged detail views for better illustrating my improvements.

35 A A represent the transverse, and A' A' the longitudinal, frame-bars of a saw-mill. Upon one of these longitudinal bars A' an angular bracket or raised guide plate or rail, B, having pendent ears or lugs B' extending down 40 upon either side of the bar A', is secured by means of bolts b b'. This guide-plate is provided along its center with a slot, B', for a purpose which will be hereinafter specified.

C C' represent slotted seat blocks or plates 45 adapted to operate in connection with the slotted bracket B, and for steadyng their movements upon such track they are provided with pendent lips or flanges c c', which project down upon either side of said track, thus holding said plates in place. The plates C C' are

further provided with other flanges, similar to those just described, but which extend upward from the upper surface of said plates, and at right angles to the pendent flanges above described. These flanges (designated by c' c') are 55 adapted to receive between their inner adjacent sides the inner ends of L-shaped or angular arms D and E, as shown in Fig. 2, whereby said arms will be guided in their movements back and forth transversely of the elevated track. The arms D and E, as before mentioned, are by preference made of angular or bell-crank form, and the former one, D, which is located farthest from the saw-shaft, is made longer, for the purpose of bringing its 60 outer end D' opposite the outer end E' of the arm E. The arms D and E are also slotted at D' and E', as shown, and bolts F F' pass through these slots, the slots in the plates C C', and the slots in the rails B, for holding the 65 blocks or plates C C' and arms D and E to the rail B, and clamping them securely thereto when in their adjusted position. The bolts F F' are provided on their lower extremities with 70 square heads F', which fit between suitable 75 flanges or pendent ribs, b' b'', cast or otherwise formed upon the lower face of the track B, and extending any desired length, preferably of the same length as the slot B', thus forming a guideway for the head of the bolts F F' and 80 preventing the turning of the latter. The outer ends of the bell-crank arms are provided with slotted enlargements D' E', as shown, and both being of the same form and for one 85 and the same purpose, it is necessary to describe only one of them. The slotted portion D' of the arm D is of a size suitable for the reception of a block or bearing-piece, D'', of 90 wood or other suitable material, which is held firmly in place by means of an adjustable screw and bearing-plate, d'. The plate d' is angular in form, or, in other words, has short flanges d' d' at its ends, which overhang the wall of the slot and prevent displacement of the plate when the bearing-block D'' is adjusted end- 95 wise for any cause. The screw d' works in a threaded perforation in the portion D' of the arm D, and bears with its end against the plate d', the latter serving to firmly clamp the bearing-block D'' in place, while at the same 100

time facilitating its adjustment. It is intended when the arms D and E are properly adjusted that the bearing-blocks D² and E² shall bear lightly against the surface of the saw, and as near the cut of the same as practicable; and also that they shall be in an exactly-opposite relation one to the other upon opposite sides of the saw, as shown clearly in Fig. 2. When the arms D and E are so adjusted, their blocks or seats C C' will be brought together, one abutting against the other. This is a great advantage, as it will be apparent that the seat C, which is farthest from the saw-shaft, may be released by loosening the nut or bolt F, and be moved along the guide plate or track B until its enlarged outer end, containing the bearing-block D², is carried beyond the teeth of the saw G, thus allowing the saw to be removed without disturbing the other arm, E, of the saw-guide. When the saw is again replaced, the seat C, above referred to, may be moved back along the raised guide-plate B until it reaches and is stopped by the other seat, C', when, as before mentioned, the bearing-block D² will be exactly opposite the block E², thereby facilitating the readjustment of the guide. The angular guide-arms D and E are adapted to be adjusted upon their adjustable seats C C', as follows, viz: The arms D and E are provided at their inner ends with pendent ears d d, as shown in Fig. 4, and the seats C C' are provided with adjustable screws c², which have upon them suitable flanges, c³ c⁴, located at such a distance apart that they are adapted to receive between them the ears d d, above referred to.

It will be seen that by turning the screws c² the arms D and E, through the medium of the parts just described, will be adjusted transversely of the saw, and when brought into the desired relation to the same they may be clamped and held secure by means of the bolts F and F', hereinbefore referred to.

Having now described my invention, what I claim, and desire to secure by Letters Patent, is—

1. In a saw-guide, the slotted guide plate or rail B, secured to the frame in which the saw is mounted, upon one side thereof, and provided with the sliding independently-adjustable seat-blocks C and C', in combination with the slotted arms D and E, adjustably secured to said seat-blocks, for the purpose and substantially as described.

2. In a saw-guide, the flanged seat-blocks C and C', sliding and adjustable independently of each other upon the slotted guide plate or rail B, upon one side of the saw, in combination with the angular guide-arms D and E, 60 adjustably secured upon said independently-adjustable seat-blocks, and means, substantially as described, for adjusting said guide-arms upon said flanged seats, substantially as described. 65
3. In a saw-guide, the guide-arms D and E, adjustable upon and in combination with the seat-blocks C and C', independently adjustable upon the guide-plate B, secured to the frame, upon one side of the saw, whereby one 70 of said arms, D, may be removed beyond the cut of the saw by sliding the seat-block C upon rail B, and the saw detached without adjustment of arm E, substantially as described. 75
4. In a saw-guide, the angular arms D and E, 75 adjustable in the manner and by the means substantially as shown and described, and provided at their outer ends with slotted enlargements D² E², in combination with bearing-blocks D² E², located in said slotted enlargements, and held in place by the flanged plates d and screws d², whereby the said blocks D² may be adjusted laterally in their slots to accommodate the saw, substantially as described. 80
5. In a saw-guide, the angular guide-arms 85 D E, provided with pendent ears d d and slots D', in combination with the adjustable flanged seat C and C', slotted at C², and provided with the screw c², having the collars c³ c⁴, and the bolts F F', all arranged and operating in the 90 manner and for the purpose substantially as described. 95

6. In a saw-guide, the slotted elevated guide-plate B, secured to the frame, and provided with the pendent flanges b² b², in combination 95 with the slotted seat-blocks C and C', provided with flanges c c' c', the slotted guide-arms D and E, and through-bolts F and F', passing through the slots in the said arms, seat-blocks, and guide-rail, all for the purpose and 100 substantially as described.

In testimony whereof I have hereunto set my hand this 24th day of November, A. D. 1883.

WALTER J. F. LIDDELL.
